UNITED STATES PATENT OFFICE

126,216

DESIGN FOR A MATTRESS COVER OR SIMILAR ARTICLE

Allen C. Weissman, New York, N. Y.

Application January 18, 1941, Serial No. 98,176

Term of patent 3½ years

To all whom it may concern:

Be it known that I, Allen C. Weissman, a citizen of the United States and a resident of the city of New York, in the county of New York and State of New York, have invented a new, original, and ornamental Design for a Mattress Cover or Similar Article, of which the following is a specification, reference being had to the accompanying drawing, forming a part thereof.

The figure is a plan view of the mattress cover or similar article showing my new design.

I claim:

The ornamental design for a mattress cover or similar article, substantially as shown.

ALLEN C. WEISSMAN.
